UNITED STATES PATENT OFFICE.

EDWARD CLAXTON WALTER, OF ORANGE, NEW JERSEY, ASSIGNOR TO THE ELLIOTT-FISHER COMPANY, OF NEW YORK, N. Y., A CORPORATION OF DELAWARE.

SELECTING MECHANISM FOR CALCULATING MACHINES.

Application filed April 21, 1925. Serial No. 24,771.

This invention relates to a selecting mechanism for calculating machines of that type in which selecting elements are set by keys and subsequently operated to throw the key 5 selected values into denominational members or index wheels.

The object of the invention is to provide a machine of this character with simple and efficient selecting mechanism, occupying a 10 minimum of lateral space to permit close spacing of the index wheels and capable of being set without necessitating conjoint movement of a plurality of setting members.

A subordinate object is to arrange the setting members so that they will normally occupy positions at one side only of the index wheel with which they are associated and equipped with complements of teeth so arranged that any value from 1 to 9 may be obtained by the setting of a single member upon the depression of a single key. Subordinate objects will hereinafter appear.

In the accompanying drawings:

Figure 1 is an elevation of an index wheel 25 and its associated selectors.

Figure 2 is a transverse sectional view showing the relation of the selectors and index gear.

Figure 3 is a view of the index wheel, its 30 gear and the associated selecting elements, and

Figure 4 is a plan view showing a plurality of index wheels, the associated selecting mechanism and the bank of keys associated with 35 one denominational position.

Mounted on a shaft 1 are a plurality of denominational members or index wheels 2, with each of which there is associated a gear 3. Rotatable with two selector shafts 4 and 40 5, and slidable endwise thereof, are selecting members, or selectors 6 and 7 of cylindrical form, equipped with teeth 8.

The teeth 8 of the selectors are spaced in accordance with the spacing of the teeth of 45 the gear 3 so that when a tooth or teeth of either selector is located in the plane of the gear, the rotation of the selector shafts will rotate the index wheel, a number of increments corresponding to the selected value.

50 The teeth 8 of the selector 6 are four in number and are graduated, as shown in Figure 3, so that the first increment of movement to the left or in the direction of the gear will bring one tooth into operative position, while 55 each successive step of movement of the selec-

tor in the same direction will bring another tooth into operative position.

The other selector 7 is equipped with nine teeth, so arranged that five of them come into action on a single step of movement of the selector, while an additional tooth comes into operative position upon each succeeding step or movement. Thus, it will be seen that the selector 6 is settable in any one of four positions to secure the values 1 to 4, while the selector 7 is settable in five positions to select the values 5 to 9.

The specific means for moving the selectors 6 and 7 is no part of my present invention. Various key operated mechanism for shifting 70 selectors step by step to different set positions are well known in the art.

However, it may be stated that the selecting mechanism herein claimed is designed for use in a well known type of calculating machine such, for instance, as that disclosed in Reissue Patent #13,841 to Baldwin, and it is contemplated to shift the selectors by mechanism operated from the keys as in Baldwin, except that, of course, obvious variations of 80 Baldwin's cam elements will be necessary to effect the described movements.

It is deemed sufficient for the purpose of this disclosure, to show, in Figure 4, a pair of bell crank shifting levers 9 and 10, arranged to shift the selectors 6 and 7 of one denomination, and shown diagrammatically as connected to the keys of one row or bank. That is to say, the selector 6 is connected to the first four keys because it selects the values 90 1 to 4, while the selector 7 is connected to the last five keys because it selects the values 5 to 9.

The means whereby a crank or motor 11 serves to rotate the shafts 4 and 5 is not material, but may include a driving gear 12, operated by the crank and meshing with a pair of gears 13 and 14 on the shafts 4 and 5.

It is thought that from the foregoing the construction, operation and advantages of 100 my selecting mechanism will be clearly understood, but I reserve the right to effect such modifications thereof as may fall within the scope of the protection prayed.

What I claim is:—

1. In a calculating machine, the combination with a denominational member, of a plurality of selectors adapted to operate said member and movable in the same direction to different set positions.

105

110

2. The combination with a denominational member, of operating mechanism therefore, including two selectors movable in the same direction to setting positions and rotatable on different axes to operate the denominational member. 5
3. The combination with a denominational member, of operating mechanism therefore, including a plurality of rotary selectors normally located at one side of the denominational member and independently movable toward said member to different set positions. 10
4. The combination with a denominational member, of an operating mechanism therefore, including parallel shafts and selectors mounted on said shafts and movable thereon in the same direction to set said selectors in operative position. 15
5. The combination with a denominational member, of an operating mechanism therefore, including laterally settable selectors normally located at one side of the denominational member, said selectors being rotatable on different axes to operate the denominational member and each having graduated projections or teeth. 20
6. The combination with a denominational member, of a gear associated therewith, a plurality of independently rotatable selectors normally mounted at one side of the plane of the gear and having teeth brought into the operative plane of said gear by the movement of the selectors in the same direction transverse to the gear, and means for rotating the selectors to operate the denominational member. 30
7. The combination with a shaft, of a denominational member mounted thereon, a gear associated with a denominational member, a plurality of shafts parallel with each other and with the shaft first named, toothed selectors rotatable with said plurality of shafts and laterally movable in the same direction to set positions with respect to the operation of the gear, and means for rotating the shafts on which the selectors are mounted. 45
8. The combination with a denominational member, of selectors normally located at one side thereof, means including keys for moving the selectors to different set positions, and means for individually rotating the selectors to operate the denominational member. 50
9. The combination with a denominational member, of a plurality of selectors movable in the same direction to different set positions, separate keys for setting said selectors and operating means common to both selectors to individually rotate the same. 55
10. The combination with a denominational member, of a plurality of rotary toothed selectors mounted at the same side of the denominational member on different shafts, separate keys for moving each of the selectors toward the denominational member to different set positions, and means common to both selectors for rotating the same. 60
11. The combination with a denominational member and a gear of two rotary selectors mounted on different axes and normally located at the same side of the gear, one of said selectors having teeth of graduated lengths, and the other of said selectors having teeth of graduated lengths and also a plurality of teeth terminating in the same plane, means for shifting the said selectors laterally to different set positions, and means for rotating the selectors. 70
- 75

In testimony whereof, I affix my signature.

EDWARD CLAXTON WALTER.
